(57) **CLAIM**

The ornamental design for the package lid, as shown and described.

DESCRIPTION

FIG. 1 is a perspective view of a package lid of the present invention;

FIG. 2 is a top plan view of the package lid of FIG. 1;

FIG. 3 is a side elevational view of the lid of FIG. 1;

FIG. 4 is an end elevational view of the lid of FIG. 1; and,

FIG. 5 is a bottom plan view looking up into the package lid of FIG. 1.
